[57] CLAIM

The ornamental design for an electrical switchgear module for power distribution systems, as shown and described.

DESCRIPTION

FIG. 1 is a perspective view of an electrical switchgear module for power distribution systems showing our new design;

FIG. 2 is another perspective view of the electrical switchgear module for power distribution systems of FIG. 1 taken from a different point of reference;

FIG. 3 is a top plan view thereof;

FIG. 4 is a bottom plan view thereof;

FIG. 5 is a front elevational view thereof;

FIG. 6 is a right side elevational view thereof, the left side elevational view being a mirror image of FIG. 6; and,

FIG. 7 is a rear elevational view thereof.
